SHOE POLISH CONTAINER AND ENCLOSED
BRUSHPhilip Lewis and Nicholas Sherhefer,
New York, N. Y.

Application July 15, 1939, Serial No. 284,620

3 Claims. (Cl. 15—258)

This invention relates to a container for shoe polish having means to contain a polishing brush therewithin.

It is an object of this invention to provide a device in which space is provided in the wax polish containing portion of the container, to house the bristled end of a brush, and space is provided in the inner top portion of the container to house the handle of said brush.

It is a further object of this invention to provide a method of filling the wax containing portion of the container so as to provide space therewithin, for the bristled end of a brush.

It is still a further object to provide a container cover having mounted thereon a brush for shoe polish packed within the base of the container.

These and other objects will appear clear from the following description and attached drawing, forming part thereof.

Fig. 1 is a perspective view of the parts showing the relationship of one to another, the parts being bracketed.

Fig. 2 is a cross-section of the wax container and lower portion of the container taken on the line 2—2 of Fig. 1.

Fig. 3 is a cross-section view similar to Fig. 2 showing an embodiment providing an integral wall to house the bristles of the brush.

Fig. 4 is a cross-section view similar to Fig. 2 of another embodiment providing a wall within which to house the bristles of the brush.

Referring now to the drawing, in Fig. 1, 10 represents a cover of the usual wax-shoe-polish-container. The lower and wax containing part of the can 11, has a suitable tubular ring 12, in the center portion, of suitable material, providing a space for the bristles 13, of a shoe polishing brush having handle, 14. The usual can-opening lever 15, may be provided on the side flange of the top of the can. While we have shown the brush as a separate member, it is understood it may be mounted integral with the cover, and the cover may provide a handle means for the brush in place of the aforementioned handle 14. The tubular-ring-wall means 12 may be formed integral of the base of member 11 by being depressed therein as shown in Fig. 3, or it may be formed separate and fixed to the bottom of member 11 by solder or other means. It is seen that there is sufficient space within the cover member for the handle 14.

In filling the container with the wax polish contents, we prefer to first set the ring 12 in place in the center and hold it there with suitable means while pouring the molten wax there-

around. It is seen that there is preferably poured and formed, a ring of wax shoe polish 16, and the difference between its outer and inner diameters is wider than the diameter of the bristled portion of the brush to permit removal of all of the wax in the can by the contact of the brush therewith.

While we have shown a ring 12 of fibre material, said ring may be formed of similar wax polish and inserted in the can in its tubular form, and it may have an outer coating of a thin layer of a heat-resisting material on cylindrical surface 121, to resist the action of heat of the thereafter poured therearound molten wax polish 16 with which it becomes in contact.

Another method of providing a space for the bristles which has been found satisfactory, is to first completely fill the member with molten wax, and then permit the wax to cool and harden, and then to drill out a center portion to provide space for the bristles of the brush.

Other methods may be utilized to fill member 11 in order to provide space for the bristles. In operation, the can, with its cover tightly in place, 25 is opened by lifting one end of the lever 15 upwardly and springing the cover off the base flange 111 against which the other end of the lever acts and removing the cover. The brush is then in position for handling, and may be removed, and its bristles may be contacted with the wax causing same to adhere therewith.

Parts may be used without others. The disclosure is intended to be illustrative, rather than limitative.

35 We claim:

1. In a shoe polish container the combination of a base cup and a cover therefor slidably removable from said base cup, a tube of shoe-polish-like-material in said base, a brush having handle and bristles housed within said container, said tube providing a side wall housing for the bristles and said cover housing the handle, an additional tube of paste material adjacent the cylindrical inner wall surface of the first tube, said inner tube having a coating of material having a higher melting point than the first tube material, the tubes and coating being frangible to wear away as the paste is used and together providing a flat upper wearing surface contactable by the bristles when moved in a straight line across the outer diameter of said flat surface.

2. In a shoe polish container the combination of a base cup and a cover therefor slidably removable from said base cup, a tube of shoe-polish-like-material in said base, a brush having handle

and bristles housed within said container, said wax tube providing a side wall housing for the bristles and said cover housing the handle, said tube being frangible to wear away as the paste is used and providing unobstructed upper wearing surface contactable by the bristles when moved in a straight line across the outer diameter of said paste tube surface, said brush being attached to said cover.

3. In a shoe polish container the combination 10
of a base cup and a removable cover cup there-
for, a tube of wax-like material in said base, a

brush having handle and bristles housed within said container, said wax tube housing the bristles and said cover housing the handle, an additional tube of similar wax material having a coating of heat-resisting material on its outer surface, said added tube being adjacent the inner wall surface of the outer tube, said tube, wax and heat resistor being frangible to wear away as the paste is used on contact and attachment with said bristles.

PHILIP LEWIS.
NICHOLAS SHERHOFER.
